UNITED STATES PATENT OFFICE.

HANNAH J. K. THOMAS, OF JACKSONVILLE, FLORIDA.

PILLOW.

1,211,257.

Specification of Letters Patent.

Patented Jan. 2, 1917.

Application filed March 22, 1916. Serial No. 85,922.

To all whom it may concern:

Be it known that I, HANNAH J. K. THOMAS, a citizen of the United States, residing at Jacksonville, in the county of 5 Duval and State of Florida, have invented new and useful Improvements in Pillows, of which the following is a specification.

This invention relates to certain novel and useful improvements in pillow construction.

10 In carrying out the present invention, it is my purpose to provide a pillow which will embody a cylindrical wall and end walls for the cylindrical wall formed centrally with axial openings, a coiled spring being 15 arranged longitudinally of the pillow and having the ends thereof secured to the end walls in order to hold the end walls properly spaced apart, cup springs radiating from the coiled spring and being connected 20 to the cylindrical side wall of the pillow to hold such wall against collapsing and at the same time enable the wall to yield when the pillow is subjected to pressure, thereby enabling the pillow to be used with comfort 25 and ease. By means of the openings in the end walls of the pillow and the open springs, air may circulate through the pillow, thereby keeping the latter thoroughly ventilated.

With the above and other objects in view, 30 the invention consists in the construction, combination and arrangement of parts hereinafter set forth in and falling within the scope of the claim.

In the accompanying drawing; Figure 1 35 is a perspective view of a pillow constructed in accordance with the present invention. Fig. 2 is a longitudinal sectional view therethrough. Fig. 3 is a cross sectional view through the same. Fig. 4 is an enlarged 40 fragmentary diagrammatic view showing the arrangement of the springs.

Referring now to the drawing in detail, 1 designates the circular wall of the pillow, such wall embodying inner and outer layers 45 of fabric or cloth 2 and 3 and a pad 4 arranged between the inner and outer fabric 2 and 3. The ends of the wall thus formed are turned in and the cloth and pad secured to one another and to a circular securing

band 5 by means of rivets 6 or other suitable 50 fastening devices. These inturned ends of the circular wall constitute the end walls of the pillow and at the point where the pad and fabric are fastened together and to the circular securing band axially alining openings 55 are formed. Arranged longitudinally of the pillow at the center thereof is a coiled spring 7 having the end convolutions secured to the respective securing bands 5. Secured to the remaining convolutions of the 60 spring 7 and radiating therefrom are cone-shaped coiled springs 8. The springs 8 on each convolution of the spring 7 are spaced apart equal distances and the small ends of such springs 8 are fastened to the spring 7, 65 while connected to the large ends of the springs 8 are cone-shaped coiled springs 9 respectively. The small ends of the springs 9 are connected to the large ends of the springs 8 and connected to the large end 70 of each spring 9 at diametrically opposite points are outwardly projecting cone-shaped coiled springs 10 that have the outer or relatively large ends thereof secured to the inner cloth or fabric 2. Owing to the arrangement of the springs 7, 8, 9 and 10, it 75 will be seen that the interior of the pillow will be thoroughly ventilated at all times, while the cylindrical wall of the pillow will be held against collapsing and at the same 80 time permitted to yield when the pillow is in use. Surrounding the pillow is a slip 11 formed of some suitable material and the ends of the slip are turned in and equipped with a draw string whereby the slip may be 85 tightened around the pillow. If desired, a lace fabric 13 or the like may be connected to each end of the slip so as to ornament the pillow.

While I have herein shown and described 90 the preferred form of my invention by way of illustration, I wish it to be understood that I do not limit or confine myself to the precise details of construction herein described and delineated, as modification and 95 variation may be made within the scope of the claim and without departing from the spirit of the invention.

I claim:

A pillow comprising a circular wall having the end portions thereof inturned to form end walls and formed with axially alining openings, a coiled spring arranged within said circular wall and extending longitudinally thereof and having the end convolutions secured to said end walls respectively, and springs radiating from the con-

volutions of said coiled spring and connect- 10 ed to said circular wall.

In testimony whereof I affix my signature in presence of two witnesses.

HANNAH J. K. THOMAS.

Witnesses:

L. E. STOKES,
GILES L. MALON.
